METAL TYPE STOP MOTION ATTACHMENT
FOR LOOMS

Jonas F. Koskela, Maynard, Mass.

Application May 28, 1945, Serial No. 596,197

4 Claims. (Cl. 139—337)

1

This invention relates to a new and improved contrivance, in the form of a quick-applicable and removable attachment for looms, and the purpose thereof is to provide a new styled adjustable metal-type stop motion device for stopping a loom when a harness wire or strap breaks.

By way of introduction, it is to be pointed out that the instant invention is essentially and primarily an improvement upon a similar stop motion attachment constituting the subject matter of my U. S. Patent 2,348,824 granted to me under date of May 16, 1944. In order to better appreciate the nature of the invention it is thought advisable, at this point, to describe broadly and specifically the attachment referred to as the subject matter of Patent No. 2,348,824.

Broadly, the aforementioned prior attachment is characterized by an adapter for connection with a conventional loom frame, an inclined wire carried by said adapter, and a current conducting element which is connected with the wire and also connected with the electric stop motion constituting a conventional part of the loom.

More specifically, the attachment in my co-pending application Serial No. 483,317 is an automatically operable circuit make and break device which is characterized by an inclined wire rod or member adapted to underlie a bank of parallel correspondingly inclined harness wires, there being adapter means for supporting this wire element or rod on a predetermined part of the conventional loom frame, and further, a current conductor electrically connected with the wire and adapted to be connected to a suitable part of the conventional loom stop mechanism. The adapter is in the form of a wooden or equivalent bar which is adapted to be removably mounted between the parallel frame bars of the loom, this having V-shaped notches to facilitate application and maintenance in place, and the wire member is mounted thereon.

For reasons discovered from trial and error I have found it possible and expedient to revise and refine the construction which is the construction of the present application, this being in the form of a coiled circuit make and break wire element mounted through the medium of insulators on an inclined adapter rod, which rod is adjustably mounted on one of the loom frame bars.

Other features and advantages will become more readily apparent from the following description and the accompanying illustrative drawings.

In the drawings, wherein like numerals are

2

employed to designate like parts throughout the same:

Figure 1 is a side elevational view of a loom including a frame, harness, harness wires, pulleys for the harness wires and the usual conventional jack structure.

Figure 2 is a view, enlarged in scale, on the plane of the line 2—2 of Figure 1 looking in the direction of the arrows.

Figure 3 is a top plan view which includes the wiring diagram, the latter embodying conventional or existing type loom parts.

Figure 4 is a fragmentary view partly in section and partly in elevation to bring out the specific structural details.

Figure 5 is a section on the line 5—5 of Figure 4.

Figure 6 is a detail of the left hand end portion of the structure seen in Figure 4, this detailing the anchoring loop.

The channel-shaped loom frame bars A of the loom B have disposed thereabove the inclined bank of harness wire C, the latter being connected to the regular jack structure D and passing down over the pulleys E on the frame and being attached to the harness F. These are all conventional parts.

The novel and improved attachment is denoted by the numeral 6 and this comprises an adapter 30 in the form of a bendable metal rod 7. This is inclined and formed at its lower or left-hand end with a loop 8 adjustably secured by a bolt and nut fastener 9 to the adjacent web of the correspondingly adjacent frame bar A. This adapter is provided at opposite ends with insulators 10 and 11. The circuit make and break wire element, in this set-up is denoted by the numeral 12. This is a coiled spring having the right-hand coil anchored on the insulator 11 and the opposite coils tightened about the remaining insulator 10 as indicated at the point 13. The free end of the wire is provided with a binding post 14.

The parts 7 and 12 underlie the wires C and the circuit is closed in the same manner as disclosed in my co-pending application Serial No. 483,317.

It is perhaps desirable to explain that the so-called wiring diagram in Figure 3 embodies conventional parts of a well-known "C and K" electric warp stop motion. In this assemblage we observe a regular drop wire bar 15 which comprises an outer steel sheath 16 and an insulated inner member 17, and core member 18 extending beyond one end of the sheath. A cable of insulated wire 19 is connected with the aforesaid

binding post 14 and includes an extension wire 20 which connects with a binding post 21 on the extended end of the core member 18. The sheath 16 is suitably grounded as at 22, that is, grounded to the loom frame. In this arrangement when the hairpin-like dropwire (not shown) has fallen and has acted as a switch to close the electrical circuit, the solenoid 23 in the knockoff box (not shown) is automatically energized and comes into play, stopping the loom in the conventional manner. The numeral 24 designates a hand switch, 25 a battery and 26 the ground. When the switch 24 is closed the circuit is ready for operation. Therefore, should any one of the wires C get loose and fall down on the coiled member 12 this closes the circuit and stops the loom.

The loop and bolt arrangement for the adapter member 6 permits the entire attachment to be raised and lowered in respect to the frame bar A and the overlying harness wires C. The rod member 7 is sufficiently flexible to permit it to be bent to vary the angularity to better place said part beneath the wires C. Using the coils or convolutions in the circuit make and break wire 12 renders the same more effective in tripping and catching the falling wires C.

The attachment may be used singly or in pairs, as desired. It is located on the top of the loom away from dust and lint and has but a single simple slanting wire arrangement to accomplish the desired purposes. I have not attempted to stress the wiring arrangement since it is merely shown to assist in generally understanding the operation of the invention. The invention is the attachment and the attachment comprises the adapter, means for adjustably mounting it in place, the insulators and the coiled wire 12 attached to the insulators and surrounding the rod or wire member 7.

It is thought that persons skilled in the art to which the invention relates will be able to obtain a clear understanding of the invention

after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

- 10 1. An attachment of the class described comprising a longitudinally coiled circuit make and break wire adapted to underlie a bank of overhead harness wires, and an adapter and supporting element for attaching said wire to a predetermined part of the loom frame.
- 20 2. An attachment for looms comprising an adapter including a longitudinally elongated limb having an attaching loop at one end for adjustable connection with an adjacent loom frame bar, and a convolved circuit closing wire surrounding said limb in the manner and for the purposes described.
- 25 3. An attachment of the class described comprising an adapter including an inclined longitudinally elongated limb having means at one end for adjustable mounting on a loom frame bar, insulators mounted at opposite ends of said limb, and a coiled wire surrounding the limb and having its end-coils wound about and attached to said insulators.
- 30 4. A loom attachment of the class described comprising an adapter unit, said unit comprising a bendable wire rod having insulators at opposite ends, one end of said rod being bent laterally and formed into a frame attaching loop, insulators mounted on the wire rod adjacent opposite ends of said rod, and a coiled circuit make and break wire coiled around said rod and having its end coils embracing the insulators, one end of said wire being adapted for connection with a circuit conductor.

JONAS F. KOSKELA.
